LOCKING DEVICE

William F. Klemm, Detroit, Mich.

Application September 3, 1946, Serial No. 694,651

6 Claims. (Cl. 192—8)

1

This invention relates to clamping fixtures, and more particularly to clamping fixtures adapted to clamp an object with a predetermined clamping force and to lock the fixture against release.

The main objects of the present invention are: to provide an improved clamping fixture adapted to clamp an object with a predetermined clamping force and then lock in position to prevent damage to or release of the object clamped; to provide an improved clamping fixture of the above generally indicated type which is simple in construction, economical of manufacture and assembly, and reliable and efficient in operation; to provide a clamping fixture with improved means for readily adjusting the fixture to lock in position upon the application of any desired predetermined clamping force upon an object to be clamped; and to generally improve the construction and operation of clamping fixtures of the above generally indicated type.

Other objects and features of novelty of the invention will be specifically pointed out or will become apparent when referring, for a better understanding of the invention, to the following description taken in conjunction with the accompanying drawings, wherein:

Fig. 1 is a plan view showing parts in section, of a clamping fixture embodying features of this invention;

Fig. 2 is a sectional view of the structure illustrated in Fig. 1, taken substantially along the line 2—2 thereof;

Fig. 3 is a sectional view of a clamping fixture, similar to that illustrated in Fig. 1, showing a further form which the invention may assume;

Fig. 4 is a sectional view of structure, similar to that illustrated in Fig. 3, showing a further form which the invention may assume;

Fig. 5 is a sectional view of another form of clamping fixture which embodies features of the present invention;

Fig. 6 is a sectional view of still another form of clamping fixture embodying the invention;

Fig. 7 is a sectional view showing an alternative means for mounting one end of the shaft of a clamping fixture embodying the invention;

Fig. 8 is a sectional view of an improved threaded form for a clamping fixture embodying the invention, and

Fig. 9 is a view in elevation of still another form of clamping fixture.

Referring to Figs. 1 and 2 of the drawings, the clamping fixture 10 comprises a base 12 having a flat portion 14 adapted to support the object to

2

be clamped and serve as one of the clamping jaws. At one end of the base 12, a housing 16 is integrally formed thereon for slidably supporting two vertically disposed parallel columns 18 and a horizontally disposed shaft 20. Each of the columns 18 has a vertically disposed rack 22 formed along one side thereof, and the shaft 20 has an elongated spur gear 24 integrally formed thereon which continuously meshes with the racks 22 for moving the columns 18 vertically in the housing 16 when rotated. At their upper ends, each of the columns 18 is provided with an upwardly projecting stud 26 which extends through the plate 28 and receives a nut 30. The plate 28 serves as a second clamping jaw and cooperates with the flat portion 14 of the base 12 to clamp an object therebetween.

One end of the shaft 20 has a head 32 integrally formed thereon adapted to engage the housing 16 in which the shaft is rotatably supported. Adjacent to its other end, the shaft has a threaded portion 34 which extends outwardly of said housing. A handle 36 is threaded on said portion 34 and has a cylindrical bore 38 formed in its outer end. One end of a compression coil spring 40 is received in said bore for engagement with said handle and the other end is received in a recess of a nut 42 threaded on the outer end of the shaft 20. The nut 42 may be adjusted on the shaft 20 to produce any desired compression in the spring 40 and may be securely held in that position by an Allen head set screw 44 or like means.

In the construction above described, when an object to be clamped is placed between the jaws 14 and 28 and the handle 36 is rotated in a counterclockwise direction as viewed from the right in Fig. 1, the shaft 20 is caused to turn with the handle as a result of the frictional engagement between the threads on the handle 36 and the threads on the shaft 20. The amount of this frictional force may be varied by adjusting the nut 42 to alter the compression of the spring 40, as above described. This rotation of the handle 36 and the shaft 20 drives the column 18 vertically downward, as viewed in Fig. 2, through the engagement of the spur gear 24 and the racks 22. The jaw 28 is moved toward the jaw 14 in this manner until a predetermined amount of gripping force is applied to the object held therebetween, at which time the handle 36 begins to turn relative to the shaft 20 to be advanced on the threaded portion 34 of the shaft toward the head 32 until the head 32 and the handle 36 grip opposite sides of the housing 16 and thereby

prevent further rotation of the handle. This produces a wedging action between the threads on the handle 36 and those on the shaft 20, and a pressure between handle 36 and the housing 16 which combine to lock the handle 36 in position against inadvertent movement in a clockwise or releasing direction. Further movement of the handle 36 in a clamping or counterclockwise direction is positively prevented by this locking engagement.

When desired the clamp may be easily released by rotating the handle in a clockwise direction. This causes the handle 36 to advance along the shaft 20 until the housing 16 is no longer gripped between the head 32 and the handle 36, after which the shaft 20 turns with the handle 36 as a result of the frictional force developed between the handle 36 and the shaft by the spring 40 as described above.

It will be apparent that if right-hand threads instead of the left-hand threads illustrated are employed on the shaft 20, the clamping action will be effected by rotating the handle in the opposite direction. The direction of movement of the clamping jaws for a given movement of the handle may also be reversed by disposing the shaft and associated gear on the opposite side of the columns from that shown.

In the modified form of the invention illustrated in Fig. 3, the shaft 50, corresponding to the shaft 20, extends between the vertically disposed columns 52, corresponding to the columns 18, and the gear 54 carried by the shaft 50 engages a rack formed on one of the columns 52. The handle 56, corresponding to the handle 36, has a blind bore 58, the outer portion of which is threaded. This form of the invention is particularly adapted for clamping fixtures in which a relatively light clamping force is desired, and accordingly a small and relatively weak compression coil spring 60 is disposed within the inner portion of the bore 58. One end of the spring 60 engages the handle at the inner end of the bore 58 and the other end of the spring 60 engages the outer end of the shaft 50 upon which the handle 56 is threaded. The spring 60 functions to produce a frictional engagement between the handle 56 and the shaft 50 corresponding to but much smaller than the frictional engagement between the handle 36 and the shaft 20 in the embodiment described above.

In the modification illustrated in Fig. 4, the handle 62 differs from that of the construction shown in Fig. 3, in that the blind bore formed therein has an internal portion 64 which is threaded for engagement with the threaded end of the shaft 66 and an outer portion 68 which is enlarged to receive a coil spring 70. The spring 70 surrounds the shaft 66 and one end thereof engages the gear 72 and the other end engages the handle 62 at the inner end of the outer enlarged portion 68 of the bore. This larger spring 70 permits a greater clamping force than the spring 60 while both features are designed for a set load that can only be changed by changing the springs.

Another form of the invention is illustrated in Fig. 5, that wherein a fixture employs a shaft 80 having a tapered head 82 corresponding to the head 32 and a gear 84 engaging a rack 86 formed on a single column 88. The portion of the shaft 80 extending outwardly of the handle 90, which is threaded thereon, has an axially extending groove formed therein which receives a complementary tongue formed on an inner spring sup-

port member 96. The member 96 is slidable axially of the shaft 80 and has a conically shaped surface 98 on the inner side thereof adapted to engage a complementary conical seat 100 formed on the handle 90. A nut 102, similar to the nut 42, is threaded on the outer end of the shaft 80 and a compression coil spring 104 is supported between the inner spring supporting member 96 and the nut 102.

10 It will be appreciated that the clamping fixture of Fig. 5, permits a substantially greater clamping force to be applied to the object being clamped than is possible with the clamping fixtures so far described. This results from the 15 additional frictional force which is set up between the conical surface 98 of the inner spring member 96 and the conical seat 100 formed in the handle 90 which must be overcome in addition to the frictional force of the threaded engagement between the handle 90 and the shaft 80 before the handle may turn relative to the shaft and advance along the shaft to grip the housing 106 between the head 82 on the shaft and the handle 90.

20 25 These frictional forces effective to cause the handle 90 and the shaft 80 to turn as a unit may be varied in this construction as in the embodiment illustrated in Figs. 1 and 2, by adjusting the outer spring support 102 along the shaft 80 to vary the pressure of the spring 104.

25 30 The form of the invention illustrated in Fig. 6 differs from the construction shown in Figs. 1 and 2 in that a torsional spring 110 is employed, having its inner end anchored in the handle 112 and its outer end anchored in a nut 114 threaded on the outer end of the shaft 116. The spring 110 is arranged to apply a torque to the nut 114, 35 tending to thread the nut outwardly on the shaft 116 and the nut 114 is held against movement in that direction by a second nut 118 threaded on the outer end of the shaft 116.

35 40 45 In this construction, when the handle 112 is rotated in a clamping direction or in a counterclockwise direction, as viewed from the right in Fig. 6, the torque action of the spring 110, resisting further winding up of the spring, causes the shaft 116 to turn with the handle until the clamping force applied is such that the force required to turn the handle 112 is greater than the torque action of the spring 110, at which time a handle 112 turns relative to the shaft 116. The spring 110 thereafter is further wound up until the handle 112 and the opposite end of the shaft grip the housing 119 and prevent further movement of the handle as in the above described structures.

50 55 60 65 Fig. 7 illustrates an alternative means which may be mounted on the end of the shaft opposite to that which receives the handle and which replaces the heads 32 and 82 integrally formed on the shafts in the constructions illustrated in Figs. 1 and 5, respectively. This alternative means comprises a nut 120 threaded on an outwardly extending portion of the shaft 122 and secured against rotation relative thereto by a cotter pin 124. The nut 120 grips the housing 126 in the same manner as does the head 32 and may be removed to permit the shaft 122 to be inserted from either side of the housing 126.

70 75 Fig. 8 illustrates a modified form of thread construction which may be employed in any of the above described clamping fixture constructions to materially increase the clamping force which may be applied thereby. In this construction the threads are formed with a substantially

increased thread angle, said angle being that between adjacent thread faces 130 and 132. The depth of the thread is reduced by providing flats 134 at the bottom of the threads and similar flats 136 at the apex. This construction provides a substantially increased wedging action between the threaded elements and therefore a substantially greater frictional force therebetween which must be overcome before one element may turn relative to the other.

As illustrated in Fig. 9, the invention is readily applicable to clamping fixtures having a C-shaped base 140, the upper arm 142 of which carries one clamping jaw 144. In this construction the plate 146, mounted on the column 148 corresponding to the column 18, serves as the lower clamping jaw and the movement of the column 148 in a clamping direction is upwardly, as opposed to the construction shown in Figs. 1 and 2 in which the column 18 moves downwardly when moving in a clamping direction. This type of clamping device is readily adopted on the comparison microscope illustrated, described and claimed in my co-pending application, Serial No. 573,432, filed January 18, 1945. Assurance is had that the specimens examined are clamped with a like pressure and that no damage results thereto from the clamping operation.

What is claimed is:

1. In a clamping fixture, a pair of relatively movable elements employed for clamping an object therebetween, a rack mounted on one of said elements, gear means adapted to engage said rack mounted on the other of said elements, a shaft operatively connected to said gear means and having a threaded portion on one end thereof, a handle having a threaded engagement with said threaded portion, means biasing said handle axially of said shaft, and gripping means operable upon the application of a predetermined clamping force upon said object by said elements to grip one of said elements and lock said handle against further movement in a clamping direction.

2. In a clamping fixture, a pair of relatively movable elements employed for clamping an object therebetween, a rack mounted on one of said elements, gear means adapted to engage said rack mounted on the other of said elements, a shaft operatively connected to said gear means and having a threaded portion on one end thereof, a handle having a threaded engagement with said threaded portion, adjustable means for variably biasing said handle axially of said shaft, and gripping means operable upon the application of a predetermined clamping force on said object by said elements to grip one of said elements and lock said handle against further movement in a clamping direction.

3. In a clamping fixture, a pair of relatively movable elements employed for clamping an object therebetween, a rack mounted on one of said elements, gear means adapted to engage said rack mounted on the other of said elements, a shaft operatively connected to said gear means and having a threaded portion on one end thereof, a handle having a threaded engagement with said threaded portion, means including a coil spring biasing said handle axially of said shaft, and gripping means operable upon the application of a predetermined clamping force upon said objects by said elements to grip one of said elements and lock said handle against inadvertent movement.

4. In a clamping fixture, a pair of relatively

movable elements employed for clamping an object therebetween, a rack mounted on one of said elements, gear means adapted to engage said rack mounted on the other of said elements, a shaft operatively connected to said gear means and having a threaded portion on one end thereof, a handle having a threaded engagement with said threaded portion, a spring support mounted on said one end of said shaft, a compression spring engaging said spring support and said handle to bias said handle axially of said shaft, and gripping means operable upon the application of a predetermined clamping force upon said object by said elements to grip one of said elements and lock said handle against inadvertent movement.

5. In a clamping fixture, a pair of relatively movable elements employed for clamping an object therebetween, a rack mounted on one of said elements, gear means adapted to engage said rack mounted on the other of said elements, a shaft operatively connected to said gear means and having a threaded portion on one end thereof, a handle having a threaded engagement with said threaded portion, a spring support mounted on said one end of said shaft, a compression spring engaging said spring support and said handle to bias said handle axially of said shaft, and gripping means operable upon the application of a predetermined clamping force upon said object by said elements to grip one of said elements and lock said handle against inadvertent movement, said gripping means including a head formed on the other end of said shaft from said thread and an integral portion on said handle having a surface adapted to abut the opposite side of said one of said elements from the head to clamp said last element therebetween.

6. In a clamping fixture, a pair of relatively movable elements employed for clamping an object therebetween, a rack mounted on one of said elements, gear means adapted to engage said rack mounted on the other of said elements, a shaft operatively connected to the gear means and having a threaded portion on one end thereof, a handle received on said threaded portion and having a threaded engagement therewith, a spring support threaded on said one end, said spring support being adjustable along said threaded portion and having a setscrew for securing said spring support in an adjusted position, a coil spring engaging said spring support and said handle to bias said handle axially of said shaft, and gripping means operable upon the application of a predetermined clamping force upon said object by said elements to grip one of said elements and lock said handle against inadvertent movement.

7. In a clamping fixture, a pair of relatively movable elements employed for clamping an object therebetween, a rack mounted on one of said elements, gear means adapted to engage said rack mounted on the other of said elements, a shaft operatively connected to said gear means and having a tapered head on one end thereof and a threaded portion on the other end thereof, a handle having a threaded engagement with said threaded portion, means operatively connecting said handle to said shaft to cause said handle and said shaft to turn as a unit until said object is clamped between said elements with a predetermined clamping force, gripping means operable when said object is clamped with said predetermined clamping force to grip one of said elements and lock said handle against inadvert-

tent movement, said first named means including a spring support mounted on said shaft, a conical member having a tongue and groove connection with said shaft to prevent relative rotation between said shaft and said member, and a spring engaging said spring support and said conical member to urge said conical member against said handle and bias said handle axially of said shaft, said handle being formed to provide a conical seat adapted to engage said conical member.

8. In a clamping fixture, a pair of relatively movable elements employed for clamping an object therebetween, a rack mounted on one of said elements, a gear means adapted to engage said rack mounted on the other of said elements, a shaft operatively connected to said gear means and having a threaded portion on one end thereof, a handle mounted on said one end of said shaft and having a threaded engagement therewith, a spring support mounted on said one end of said shaft, means preventing rotation of said spring support relative to said shaft in at least

one direction, a torsional spring having one end anchored in said spring support and the other end anchored in said handle and being effective to cause said handle and said shaft to turn as a unit until said object is clamped between said elements with a predetermined clamping force, and gripping means operable upon the application of said predetermined clamping force to grip one of said elements and lock said handle against inadvertent movement.
